(57) **CLAIM**

The ornamental design of a ratchet wrench, substantially as shown and described.

DESCRIPTION

FIG. 1 is a perspective view of a ratchet wrench showing my new design.

FIG. 2 is a top view thereof.

FIG. 3 is a front end view thereof.

FIG. 4 is a rear end view thereof; and,

FIG. 5 is a side view thereof.

The broken lines are for illustrative purposes only and form no part of the claimed design.
